CLAIM

The ornamental design for a cigar ashtray assembly as shown and described.

DESCRIPTION

FIG. 1 is a top perspective view of a cigar ashtray assembly; FIG. 2 is a top plan view thereof; FIG. 3 is a front elevation view thereof, which is the same as the left side elevation, right side elevation, and rear elevation views; FIG. 4 is an exploded front elevation view thereof, which is the same as the left side elevation, right side elevation, and rear elevation exploded views; FIG. 5 is a partially-exploded top perspective view thereof; FIG. 6 is a top perspective view thereof with unclaimed environment shown; and, FIG. 7 is a partially-exploded top perspective view thereof with unclaimed environment shown.

The broken lines in FIGS. 6-7 are for the purpose of illustrating environment that forms no part of the claimed ornamental design. The bottom view is not shown, and no claim is made thereto.

1 Claim, 7 Drawing Sheets
